11743; and Benjamin Shmurak, 15 Stuart St., Lyn-
brook, N.Y. 11563

Filed Mar. 23, 1965, Ser. No. 84,405

Term of patent 14 years

(Cl. D26—1)

FIG. 1

FIG. 2

FIGURE 1 is a front elevational view of a 1/2 rack metered power supply module showing our new design;

FIGURE 2 is a fragmentary top plan view thereof; and

FIGURE 3 is an isometric view thereof.

The essential features of our design are shown in full lines.

We claim:

The ornamental design for a 1/2 rack metered power supply module, as shown and described.
